SOLE FLAP SPLITTING MACHINE

Robert F. Lane, Beverly, Mass., assignor to United
Shoe Machinery Corporation, Flemington,
N. J., a corporation of New Jersey

Application June 4, 1949, Serial No. 97,154

22 Claims. (Cl. 12—16.5)

1

This invention relates to splitting machines and is herein illustrated as embodied in a machine suitable for use in cutting a heel-breast-covering flap from a portion of a shoe sole.

It has been almost the universal practice for years to split heel-breast-covering flaps from soles by the use of the Empire splitter prior to shank reducing said soles, the split flaps being temporarily cemented back upon the soles from which they are split to insure that the flaps shall not be damaged during the subsequent shank reducing operation.

In order to split flaps from soles which have been operated upon, for example, by a combined rounding, shank reducing and roughing machine such as disclosed in United States Letters Patent No. 2,081,961, granted June 1, 1937, on an application filed in the name of Ernest W. Stacey, and in order to split flaps from shank reduced soles thereby avoiding having temporarily to cement the flaps back upon the soles preparatory to their being shank reduced as above explained, machines have been proposed having a stationary work support or table such as is used in the Empire splitter and upon which, as above explained, most of the operators in the shoe industry have been trained.

It is an object of the present invention to provide an improved machine for quickly and effectively splitting heel-breast-covering flaps from soles which have been shank reduced, it being a further object of the invention to provide a machine which the operators of Empire splitters can quickly and effectively use without training even though, as will be hereinafter explained, certain mechanism, including the sole supporting mechanism of the machine, is quite different from corresponding mechanism of the Empire splitter.

In accordance with features of the invention, this splitting organization comprises a movable knife carrier having on it work controlling means comprising a drag bar or matrix against which the work is held positively, as well as against the movable knife, by means of a toothed supporting roll. As shown, this roll is positively driven during the cutting action in a direction opposite to the direction of movement of the knife to hold the work against the latter and at substantially the same speed or sometimes at a slightly greater speed. Preferably, and as shown, provision is made for tilting the drag bar at the first part of the return movement of the knife to release the pressure on the flap and hence the danger of stretching it. At the same time, the supporting roll is depressed so that it is no longer effective

2

to hold the sole up against the knife and is turned backward to prevent any drag upon the sole.

Still another feature of the invention relates to the cutting of reinforced flaps which have a thicker central portion designed to render the flap stronger and intended to help to fill the middle space on the breast face of the covered heel.

To this end a retractable modifying device is associated with the matrix recess of the drag bar and means is provided to render this device progressively more or less effective in time relation to the progressive splitting action. In the illustrated embodiment, the drag bar has a matrix recess into which the mid portion of the sole is pushed by means of an enlarged portion of the supporting roll. Furthermore, the action is controlled by providing a modifying plate in a recess of the drag bar, which plate can be moved down to render the matrix ineffective or retracted to permit it to perform its function of producing a reinforced flap. This movement is effected, in the illustrated machine, by mounting the above-mentioned plate on a spring-retracted rod extending diagonally through the drag bar and arranging for control of this rod by a fixed cam during the movement of the knife carrier. Such an arrangement permits the determination of the starting point of the reinforced portion as well as the shape of that portion.

The presentation of pieces of work to the bite of the controlling members of the knife carrier is facilitated by a guide plate adjacent to said members and upon which the heel end of a sole may be rested at a point indicated by gage marks. Additionally, a fixed table is mounted at the front of the machine upon which the operator supports the toe end of a sole. The guide slides under the sole toward this table as the knife carrier moves forward and the space between the two is bridged by a flexible sheet kept continuously taut.

These and other features of the invention will best be understood from a consideration of the following specification taken in connection with the accompanying drawings in which

Fig. 1 is a side elevation of the machine;
Fig. 2 is a plan view thereof;
Fig. 3 is a front elevation of the operating mechanism with the frame cut away and in section;

Fig. 4 is an angular view of a sole having a reinforced flap;

Fig. 5 is a section through a Louis heel to which a flap has been applied and trimmed on one side;

Fig. 6 is a vertical longitudinal section taken

substantially at the center of the machine and on an enlarged scale to show the operating mechanism thereof;

Fig. 7 is a transverse section on the line VII—VII of Fig. 6;

Fig. 8 is an enlarged section similar to Fig. 6 but showing the matrix filling plate withdrawn so that the machine is adapted to produce a reinforced flap; and

Fig. 9 is a transverse section on the line IX—IX of Fig. 8.

Soles such as that shown at 20 (Fig. 4) which have been prefitted, prior to the operation of splitting a heel-breast-covering flap 22 from the heel end of the sole, will usually have been reduced in the shank portion as indicated at 24 (Figs. 7 and 9). Accordingly, since a portion of the splitting operation overlies the reduced portion of the sole, it is necessary to provide special apparatus for supporting the sole in order that a flap 23 (Fig. 6) of uniform thickness shall be split. This problem is still further intensified when the breast-covering flap is to be provided with a thickened portion or rib 26 which starts at a point spaced from the heel end of the sole, such as that indicated by the line A, and increases in width between the line A and a line B to form what is commonly termed the bullet portion of the rib and then continues from the line B to the base of the flap to form a section which is commonly called the cartridge portion of the rib. The desirability of such a rib is well understood for strengthening the heel-breast-covering flap.

Further it is shaped in such a way that it will substantially fill the space between the inturned edges of the side covering 28 of a heel 30 and will help to produce a smoothly curved surface extending along the breast surface of the heel to the top lift. After such a flap has been stuck on, the marginal portions thereof are trimmed flush with the sides of the heel as at the left side of Fig. 5 and therefore it becomes important that the margins 34 of the flap shall be thin and of uniform thickness so as to be as inconspicuous as possible.

The herein illustrated machine has a base 40 with undercut side ribs 42 as in the machine of Letters Patent of the United States No. 1,224,527, granted May 1, 1917, on the application of F. M. Furber. Slidable upon these ribs is a knife carrier 44 having an arched portion 46 and provided with a knife blade 48 (Fig. 6) which is removably and adjustably attached to the carrier 44 by means of bolts 50 on the blade passing through slots 52 in a cross member 54 of the carrier.

Power to provide a single reciprocation of this carrier for each sole is derived from a belt pulley 60 on a drive shaft 62 which has a worm 64 (Fig. 1) meshing with a gear 66 to drive an upright crank shaft 68. This crank shaft 68 is adapted to be connected to the worm gear 66 by a one-revolution clutch 70 which is controlled by a latch 72 having a treadle cord 73 and a bell crank 74 substantially as in the Furber patent just mentioned and as more fully described in Letters Patent of the United States No. 1,111,255, granted September 22, 1914, upon the application of F. M. Furber. On the upper end of this shaft 68 is a crank plate 76 provided with an undercut slot 80 so as to permit the adjustable attachment thereto, by a bolt 82, of a connecting rod 84. This rod is made in two parts so that it is adjustable in length and is pivoted upon a pin 86 in the arch 46 of the knife carrier.

As the knife carrier frame is reciprocated, a

sole is received in the bite of controlling members including a drag bar or matrix 130 and a supporting roll 90 which also holds it up to the knife. This roll, mounted on a shaft 92, is journaled in arms 93 (Fig. 6) pivoted by a shaft 124 on a roll-supporting frame 94. The frame 94 is removably held on the knife carrier 44, to facilitate assembly, by pins 96 (Fig. 2) and screws 97 (Fig. 8) and has notches 99 to permit up and down movements of the roll shaft 92. The roll arms 93 are urged upwardly against stop screws 98, when there is no work in the machine, by means of springs 100 which surround I-bolts 102 connected at their lower ends to the roll arms 93 by pivot rods 104 (Fig. 3) with the springs resting upon lugs 106 which form an integral part of the knife carrier 44.

The supporting roll comprises a series of toothed disks 110 (Fig. 7) separated by washers 112 and clamped by collars 114 upon the roll shaft 92 in positions such that the teeth of adjacent disks are not axially aligned but are staggered to permit the leather between them to be moved freely. A key 113 prevents rotation of the disks on the shaft. The extent of penetration of the teeth of the roll varies but slightly over different portions of the work and in order to make the roll more effective for supporting prefitted soles with reduced shank portions the diameters of the disks are reduced at the mid portion of the roll, as shown particularly in Fig. 3, thus providing a depression in the longitudinal contour of the roll which corresponds, broadly, to the transverse contour of the work so that a flap of uniform thickness may be split from the upper or grain surface of the sole.

In view of this toothed construction, the work is always pressed against the knife edge as rotation of the supporting roll at a peripheral speed substantially the same as the linear speed of reciprocation of the knife carrier is effected by means of gears 120 (Figs. 1 and 6) outside of the arms 93 and near the ends of the roll shaft 92. These gears mesh with pinions 122 secured to cross shaft 124 which is journaled in the roll frame 94. The two pinions 122 mesh with racks 126 which are supported upon brackets 128 (Fig. 3) attached to the sides of the base 40. The exact peripheral speed of the supporting roll 90 is determined by the relative sizes of the gears 120 and the pinions 122 and the diameter of the roll 90 and under some conditions it will be found desirable to have this peripheral speed slightly greater than the speed of movement of the knife carrier, as illustrated here, whereupon the toothed roll serves also as a feed roll.

The depth of cut of the splitting knife 48 is gaged by the drag bar 130 (Figs. 6 and 7). This bar which is of irregular shape has a rounded edge 132 which drags along the upper surface of the work. The bar is journaled at its ends in bushings 134 in the sides of the knife carrier frame 44 so that by slight turning movement of the bar it can be moved to inoperative position during the return movement of the knife carrier frame, after the flap has been split, to avoid stretching the flap.

To this end, the drag bar is provided with a screw stud 136 at its mid portion the upper end of which carries a roller 138 which is held against the inner face of a depending cam plate 140 bolted at 142 to a forward extension 144 of the connecting rod 84. A knurled screw 145 facilitates adjustment of the cam on the connecting rod before the clamp bolts are tightened. The stud 136

has restricted movement in a slot 146 of a cross bar 148 of the knife carrier frame 44 and is held in contact with the inner face of the cam plate 140 by a U-shaped spring 150 (Fig. 2), one side of which rests against a groove in the stud 136 and the other side of which is attached to the cross bar 148 of the carrier frame.

The effectiveness of this arrangement will be understood when it is considered that the crank plate 76 is in the position illustrated in Fig. 2 at 10 the beginning of the reciprocation of the knife carrier frame and turns clockwise as viewed in Fig. 2. Consequently during the first half revolution of the crank plate 76 the forward portion 144 of the connecting rod 84 is in a position such 15 that the roller 138 contacts with a concentric portion 152 of the inner face of the depending cam plate 140. This portion extends from the middle of that cam plate to its upper end as viewed in Fig. 2. Consequently the stud 136 of 20 the drag bar is held in the position illustrated in Fig. 6 so that the rounded corner 132 drags on the upper portion of the work during this half revolution of the crank shaft.

When the forward movement of the knife carrier 44 is completed, the bolt 82 joining the connecting rod 84 to the crank plate 76 causes the connecting rod to swing on its pin 86 to bring the remaining portion 154 of the cam plate surface into engagement with the roller 138 and this surface 154 controls the position of the drag bar 130 during the return movement of the knife carrier frame. The surface 154 is not concentric with the pin 86 but is relieved and consequently allows a tilting movement of the drag bar 130 upon its ends, clockwise in Fig. 6, to lift the operative edge 132 away from the work. To make it more evident that the surface 154 is relieved, an arc 156 is drawn (Fig. 2) in dash lines around the center of the pin 86.

Similarly the roll supporting arms 93 are lowered to depress the work-supporting roll during the return movement of the knife carrier frame and this is effected in a similar manner by means of a plate cam 160 which is rigidly attached to the forward extension 144 of the connecting rod and which coacts with a roller 162 mounted at the top of a tiltable frame 164 shaped like an inverted U and swingable upon pivots 166 extending between pairs of ears 168 at the forward end of the knife carrier frame 44. The side arms of this tiltable frame 164 are extended forwardly and below the pivots 166 and are forked as shown in Fig. 3 so that they may be pivotally attached to toggle links 170, the lower ends of which are pivoted to the roll supporting frame 94 by means of the same pivot rod 104 on which the eye-bolts 102 are mounted. When this tiltable frame is swung to the right as viewed in Figs. 1, 2 and 6, the forwardly bent lower ends of the side arms coact with the links 170 to make a toggle which forces down the roll arms 93 and prevents the teeth of the supporting roll 90 from pressing upward the flesh side of the sole 20 which has been treated. Even though these teeth still touch the sole during the back movement of the carrier, the reverse rotation of the roll prevents them from moving the sole longitudinally.

It will be seen from an inspection of Fig. 2 that the above-mentioned plate cam 160 has a roll engaging surface made up of two portions joined by a steep curve 172. During the forward movement of the knife carrier frame 44, the connecting rod will be in such a position that its surface 174 is 70 opposite the roller 162 and at that time the roll 75

supporting arms are held up by the springs 100 to cause the roll to engage the sole and hold it against the knife. However, as soon as the connecting bolt 82 passes dead center the steep portion 172 of the cam will be brought into contact with the roller 162 and will swing the frame 164 to the right so as to cause the before described toggle arrangement to move the roll supporting arms downward. This down position will be maintained during the remaining movement of the crank and at that time the more remote concentric surface 176 will be in contact with the roller 162 and will hold the roll-depressing frame in its forwardly tilted position but will allow it to return to upright position as shown in Fig. 6 when the crank plate 76 reaches its stopping point shown in Fig. 2.

In order that the drag bar 130 may also be utilized when it is desired to provide the sole flap with a reinforced portion 26, the drag bar is provided with a matrix mechanism including a recess 180 therein into which the mid portion of the sole may be lifted to provide the flap with a reinforced portion. This lifting of the mid portion of the sole is accomplished by a pair of toothed disks 182 which are of larger diameter than the adjacent reduced disks at the center of the roll 90 and therefore constitute a raised portion in the depression. This action is illustrated in Fig. 9.

It will be understood, however, from an earlier discussion of the formation of the reinforced flap that it is not desired that the thickened portion or rib 26 should extend through the whole length of the flap. Accordingly the drag bar is provided with a movably mounted control or modifying device in the form of a matrix-filling plate 184. This is carried by a rod 186 extending obliquely through the drag bar so that endwise movement of the rod causes the lower edge of the plate 184 to move in and out with respect to the drag bar. In its innermost or retracted position it uncovers the matrix recess 180 and in its outermost position it completely fills that recess as shown in Fig. 6 so far as bottom contour is concerned and renders the matrix ineffective. The plate is attached by screws to the rod and the rod is normally urged to the left in Figs. 7 and 9 by means of a spring 188 (Fig. 2), located in one end of the bore which receives the rod 186 and held in position therein by means of a screw 190 which has a smaller end portion or pilot 192 to help to keep this spring 188 in position and to serve as an adjustable stop determining the extent of movement of the rod 186 to the right (Fig. 7) and hence to determine the lowermost position of the plate 184.

This endwise movement of the plate carrying rod 186 is controlled by a cam strip 194 (Fig. 1) which is received in a recess of a shouldered piece 196 (Fig. 2) held by screws at the top of the left side bracket 128. The shouldered piece 196 is slotted as shown in Fig. 1 to permit adjustment of the position of the beveled end of the cam strip 194 extending between its corners 198 and 199.

Coacting with this cam strip is a roll 200 which may be supported in either of two heightwise positions in a bifurcated arm 202. The arm 202 and a superposed arm 204 are swingable upon a pivot pin 206 (Fig. 7) extending between the upper and lower lugs of a bracket 208 attached by screws to the side of the knife carrier frame 44. The forward end of the upper arm 204 has an enlarged portion 210 which is adapted to rest

against the end of the matrix plate carrying-rod 186. The upper arm 204 also has a depending lug 212 at its rear end carrying an adjustable screw 214 which rests against a shoulder on the lower arm 202. The arms are kept normally separated as shown in Fig. 2 by an interposed spring 216 permitting a slight yield between them to take care of any obstruction or of overthrow.

When the roll 200 is riding on the high portion of the cam strip 194 the matrix plate 184 is in its outermost or lower position (Figs. 6 and 7) so that the heel-breast-covering flap will be of uniform thickness. When the roll 200 slides over the end 198, 199 of the cam strip then the end spring 188 urges the rod 186 to the left into the position shown in Figs. 8 and 9 where the plate 184 does not fill the matrix recess 180 and a reinforcing rib 26 is formed on the flap. The position of the cam strip is such that when this roll 200 reaches the corner 198 of the inclined end portion of the cam strip, the drag bar 132 is alined with the line A (Fig. 4) on the drawing of the sole and when the roll has swung far enough to bring the shoulder on its arm against stop screw 214 (Fig. 2) or to permit maximum inward movement of the plate 184, it corresponds to the position of the line B. Between those two positions it has created the bullet portion of the rib and from there on to the extreme forward position of the knife carrier, the cartridge portion of the rib is formed.

Inasmuch as it is sometimes desired to utilize the machine for the formation of flaps of uniform thickness, provision is made for moving the roll 200 heightwise between the top and bottom portions of its carrier arm 202. The upper position is illustrated in Fig. 9 and the lower position in Fig. 7 and this is permitted by mounting the roll upon a pin 220 between a shoulder (Fig. 7) at the lower end of the pin and a retaining sleeve 40 222 at the top of the pin. In this retaining sleeve are two grooves, one of which is shown at 224 and a spring-pressed ball 226 is mounted in a recess of the arm 202 to retain the pin against the roll 200 either in the position shown in Fig. 9 where the roll coats with the cam strip 194 or in the lower position shown in Fig. 7 where the roll is beyond the locus of the cam and rests against the side of the shoulder strip 196, which is of uniform thickness.

Soles which are to be presented to the operating instrumentalities are positioned upon a support in the form of a table 230 extending across the front of the machine and supported upon forwardly extending bars attached to the side brackets 128 of the machine. One of these bars is an extension of the shoulder piece 196 and the other is a similarly mounted bar 232 on the opposite side of the machine. A sole is positioned upon this table in accordance with size marks 234 60 some of which are formed upon a guide plate or support 236 (Figs. 2 and 6) extending in toward the bite of the roll 90. This plate has a depending portion 238 enabling it to be attached to lugs 240 on the knife carrier frame 65 by means of screws 244. Adjacent to these screws the upper edge of the depending portion 238 is extended upwardly as at 246 to provide more metal around the screws 244. Between the supporting plate 236 and the table 230 there is 70 provided a canvas covering 248 attached at its rear edge to the depending portion 238 by means of clamp screws 250. The forward end of this canvas is guided around a roll 252 journaled in the side bars 196 and 232 and is provided with 75

a weight 254 to keep it taut as the knife carrier frame moves back and forth. It will be noted that the table has a depending portion 256 extending down in front of this weight.

By a proper choice of the toothed disks 110 and 182 from which the supporting roll is made up it will be possible to use the machine for soles having any desired transverse contour and in the operation of the machine a sole is positioned upon the table 230 with its heel end adjacent to the proper mark 234 and the treadle attached to the treadle cord is depressed. This causes the drive mechanism to effect a single reciprocation of the knife carrier frame so that the knife 48 passes through the rear portion of the sole at a level determined by the cooperating drag bar and supporting roll and it will be remembered that the supporting roll is positively driven in a direction opposite to the movement of the knife so that the operating instrumentalities travel along the sole without any substantial displacement thereof.

If a reinforced flap is to be produced, then the cam strip 194 will be properly positioned upon the bar 196 and the cooperating cam roll 200 will be raised to the position illustrated in Fig. 9 where it will cooperate with that strip to move the rod 186 in the drag bar transversely thereof during the movement of the knife through the work. This, as will be recalled, will move the plate 184 into and out of the matrix recess 180 of the drag bar to control the effectiveness thereof.

Having thus described my invention, what I claim as new and desire to secure by Letters Patent of the United States is:

1. In a splitting machine, a reciprocable carrier, a knife, a presser member adjacent to the knife and a supporting roll for holding a piece of work up against the presser member, said knife, presser member and roll being mounted on the carrier for movement along a portion of the length of the work, and means for rotating said roll at a speed proportionate to the travel of the knife to present the work to the knife without producing any substantial movement of the work.

2. In a splitting machine, a rest for a piece of work, a carrier, said carrier being provided with a knife, a presser member and a toothed supporting roll, means for producing relative movement between the work rest and the carrier to cause a splitting action along a portion of the work, and means for causing rotation of said roll to move its periphery toward the knife at a peripheral speed substantially the same as the speed of relative movement between the rest and the carrier.

3. In a splitting machine, a base, a rack on said base, a work rest on the base, a carrier, means for reciprocating the carrier along the base, a knife and an adjacent presser member on the carrier, and a rotatable toothed feed roll mounted on the carrier and geared to said rack, the top of said roll lying beneath the edge of the knife to support the work.

4. In a machine for splitting flaps from soles having reduced shank portions, a carrier, a knife blade thereon having a cutting edge in a single plane, a presser member on the carrier adjacent to the edge of said knife blade, a supporting roll on the carrier beneath the space between the edge of the blade and the presser member, said supporting roll having a toothed periphery the longitudinal contour of which has a curved recess similar to the transverse contour of the reduced shank portion of a sole, means for sliding

the knife to produce relative movement between the knife and the work, and means for rotating said supporting roll during said movement to hold the work against the knife as the knife is moved to split a flap of uniform thickness.

5. In a splitting machine, a knife, a support for the knife, means for producing relative movement between a piece of work and said knife, means for controlling the work as said relative movement takes place comprising a drag bar 10 and an opposed supporting member, a support for the controlling means, means for maintaining a fixed separation between said knife and said support for the controlling means, and means assisting the operator in the presentation 15 of a piece of work comprising a table against which the work may be gripped by the operator and a separate support for the work on the support bar, and adjacent to, the controlling means to guide the work into said means, said separate work support and the table being relatively movable as the cutting action proceeds.

6. In a splitting machine, a knife, a carrier therefor, means for producing relative movement between a piece of work and said knife, means 20 on the carrier for controlling the work as said relative movement takes place comprising a drag bar and an opposed supporting member, means assisting the operator in the presentation of a piece of work comprising a table against which the work may be gripped by the operator and a 25 separate support for the work adjacent to the controlling means and on said carrier to guide the work into said means, said support and the table being relatively movable as the cutting action proceeds, a flexible sheet stretched between said table and said support, and means for keeping said sheet taut as the above-mentioned relative movement is produced.

7. In a splitting machine, a knife, a movable carrier therefor, means for reciprocating said knife carrier, means on the knife carrier for controlling the work as said relative movement takes place comprising a drag bar member and an opposed supporting member, a supporting 40 plate on said carrier adjacent to and at a constant distance from said controlling members to guide the work therebetween, and a stationary table variably spaced from the supporting plate against which an operator may hold a piece of work during the splitting operation.

8. In a splitting machine, a knife, work controlling means comprising a drag member and an opposed supporting member, a carrier for said members, means for moving said carrier during the splitting operation, a guide plate adjacent to the controlling members and movable with the carrier, said guide plate passing under the work as the splitting action proceeds, a table spaced from the guide plate and fixed with respect to the machine, and means for bridging the space between the guide plate and the table in all positions of the carrier.

9. In a splitting machine, a carrier, a knife thereon having a cutting edge, a presser member on the carrier adjacent to the edge of said knife, means for supporting a piece of work for presentation to the knife, means for effecting relative movement between the work supporting means and the knife carrier, said presser member having a longitudinal recess, a control member movably mounted in said recess, a matrix in the periphery of said presser member, said control member being movable from a position within the presser member where the matrix is effec-

tive to a position which renders the matrix ineffective, and means for moving said control member during the presentation of the work to the knife thereby to vary the contour of the split as the cutting action progresses.

10. In a splitting machine, a carrier, a knife thereon having a cutting edge, a presser member on the carrier adjacent to the edge of said knife, means for supporting a piece of work for presentation to the knife, means for effecting relative movement between the work supporting means and the knife carrier, said presser member having a slot and an adjoining passage, a rod movable in said passage in a direction oblique to the axis of the presser member, a plate in said slot attached to said rod, said presser member having a matrix portion, and means for moving the rod axially to carry the plate from a retracted position to a position where it renders the matrix ineffective.

11. In a splitting machine, a carrier, a knife thereon having a cutting edge, a presser member on the carrier adjacent the edge of said knife, means for supporting a piece of work for presentation to the knife, means for effecting relative movement between the work supporting means and the knife carrier, said presser member having a matrix portion in its periphery and a passage oblique to its axis, a slot extending from the operative periphery of the presser member into said passage, a plate for modifying said matrix portion mounted on said rod and located in said slot, a spring urging said rod and said plate lengthwise of the presser member, and mechanically operated means for variably determining the position of said rod against the pressure of said spring as the cutting action progresses.

12. In a splitting machine, a knife, a support therefor, means for producing relative movement between a piece of work and said knife, means on the knife support for controlling the work as said relative movement takes place comprising a drag bar and an opposed supporting member, said drag bar having a matrix recess, a plate mounted thereon for in-and-out movement to fill the recess, a rod supported by the drag bar and guided for movement in a path oblique to the axis of the drag bar, a fixed cam, and means slidably engaging said cam for controlling movement of said rod to cause the plate to fill the recess as the splitting operation proceeds.

13. In a splitting machine having a base, a carrier slidable on the base, a cam mounted on the base adjacent to said carrier, a knife on the carrier, a presser member on the carrier adjacent to said knife, means for supporting a piece of work as the carrier is moved to carry the knife through a portion of the length thereof, said presser member having a matrix portion, a member movable lengthwise of the presser member for filling the matrix portion, and means operated by said cam for moving said member as the carrier is moved along the work.

14. In a splitting machine, a carrier, a knife and a work-supporting means movable with said carrier lengthwise of the machine, a matrix presser member on said carrier, a movably mounted modifying device for rendering the matrix ineffective, a movably mounted arm for operating said matrix-modifying device and having a cam roll, and a cam fixed against movement with the carrier and placed for cooperation said cam roll.

15. In a splitting machine, a carrier, a knife and a work-supporting means movable with said

11

carrier lengthwise of the machine, a matrix presser member on said carrier, a movably mounted device modifying the effect of the matrix, a movably mounted arm for operating said matrix-modifying device and having a cam roll, a cam fixed against movement with the carrier and placed for cooperation with said cam roll to cause the device to move from an ineffective to an active position, said swinging arm having a cam roll mounted upon it for displacement to either of two operative positions, one of which is beyond the locus of said cam.

16. In a splitting machine, a knife, a knife support, means for producing relative movement of translation between a piece of work and said knife, means on the knife support for controlling the work as said relative movement takes place comprising a drag bar and an opposed supporting member, said drag bar having a matrix recess, a retractable device for modifying said recess, and means operating in time relation to the movement-producing means for controlling the position of the retractable device.

17. In a splitting machine, a knife, a knife support, means for producing relative movement between a piece of work and said knife, means on the knife support for controlling the work as said relative movement takes place comprising a drag bar and an opposed supporting member, said drag bar having a matrix recess, a device associated with said drag bar and movable so as progressively to fill the recess, and means operated by said relative-movement-producing means to effect movement of said matrix-filling device.

18. In a splitting machine, a knife, a knife support, means for producing relative movement between a piece of work and said knife, means on the knife support for controlling the work as said relative movement takes place comprising a drag bar and an opposed supporting member, said drag bar having a matrix recess, a plate slidably mounted on the drag bar and arranged progressively to fill the recess, plate-carrying means movable endwise of the drag bar, and means associated with said relative-movement-producing means for effecting said endwise movement progressively during the splitting operation.

19. In a splitting machine, a base, a carrier 50 slidable on the base and provided with a knife, an adjacent presser member and a work-supporting roll, said roll being mounted on the car-

12

rier for movement toward and away from the work, means for reciprocating the carrier, and means operative during a part of said reciprocation for moving the supporting roll down away from the work.

20. In a splitting machine, a base, a carrier 10 slidable on the base, means for reciprocating said carrier, said carrier being provided with a cutting tool, a presser member and a work-supporting member, means for rendering the presser member and the work-supporting member ineffective with respect to the work, and means operated during said reciprocation for actuating said latter means.

15. 21. In a splitting machine, a base, a carrier 20 slidable on the base, a splitting tool on the carrier, a roll support tiltable on the carrier, a roll for supporting the work pivoted on said support, spring means for holding said roll support in operative position, toggle means for depressing the support to carry the roll to inoperative position, and means for reciprocating the carrier, said latter means being operative during a portion of said reciprocation to operate the toggle and depress the supporting roll out of engagement with the work.

22. In a splitting machine, a base, a carrier 30 slidable on the base, a knife and adjacent presser member on the carrier, a work-supporting member, a support for the latter tiltably mounted on the carrier, a frame pivoted to the carrier, toggle links connecting said frame to said tiltable support, a driven crank on the base, a connecting rod between said crank and said carrier for reciprocating the carrier, and a cam swingable with the forward end of said connecting rod operable to pivot said roll-depressing frame.
